HAMILTON D. LOCKWOOD, OF CHARLESTOWN, MASSACHUSETTS.

Letters Patent No. 97,659, dated December 7, 1869.

IMPROVED ARTIFICIAL NIPPLE.

The Schedule referred to in these Letters Patent and making part of the same.

To all whom it may concern :

Be it known that I, HAMILTON D. LOCKWOOD, of Charlestown, in the county of Middlesex, and State of Massachusetts, have invented an Improved Artificial Nipple; and I do hereby declare that the following, taken in connection with the drawings, which accompany, and form part of this specification, is a description of my invention, sufficient to enable those skilled in the art to practise it.

In the manufacture of rubber nipples for nursing-bottles, each nipple is formed by first cutting from sheet-rubber or rubber-compound, a blank of the proper shape, then bringing together the opposite side edges of this blank, the rubber being in a semi-plastic or viscid condition, then rolling over the other edge to form the rim of the nipple, and then vulcanizing the abutting and turned-over edges in a suitable mould.

When made of a good quality of rubber-compound, these nipples are enduring, except at one point, namely, at the part of the rim where the edges are united, but at this point the nipple soon breaks open by reason of the strain to which the rim is subjected in stretching the nipple over the neck of a nursing-bottle.

Once broken in this manner, the nipple becomes useless, as it will not cling to the bottle.

My invention has reference to overcoming this defect, and I accomplish this by placing across the seam, under the edge to be turned over, a small stay or reinforcement of thin-cloth, or other suitable material, the stay being concealed under the rolled-over edge or rim, and being securely fastened in position by the process of vulcanization.

It is an artificial nipple so made that constitutes my invention.

The drawings represent a nipple embodying the improvement, and the manner of applying the stay.

A shows the nipple before the rim is formed, or the stay applied.

B shows the nipple before the rim is formed, the stay being applied.

C shows the nipple, the rim being formed, except at the seam or stay.

D shows the finished nipple.

E shows the broken-open rim of the common nipple, as heretofore made.

a denotes the body of the nipple.

b c, the opposite edges, which, being brought and cemented together, form the seam *d*.

The nipple thus partially formed is shown at A.

A small piece *e* of fine cloth, or other material, (but preferably cloth,) is then applied to the inside of the seam at the open end of the nipple, as seen at B.

This being done, the edge is rolled over, up to the stay, as seen at C, and the stayed edge is also rolled over, all the abutting parts sticking together by reason of the viscid condition of the material. The nipple being then vulcanized in a suitable mould, is thus finished.

The stay, by the rolling-in and vulcanizing processes, is embedded within the fold, and no strain or stretch of the rim will open the seam thus reinforced.

I do not claim a nipple having a lining extending over the whole of its surface, thus having throughout a double thickness.

I claim an artificial nipple, (made of elastic material,) having its rim reinforced at the seam, substantially as described.

H. D. LOCKWOOD.
